UNITED STATES PATENT OFFICE.

WILLIAM F. QUARTERS, OF PROVIDENCE, RHODE ISLAND.

SUPPORT FOR FOOT-COVERING.

1,196,281.

Specification of Letters Patent. Patented Aug. 29, 1916.

Application filed April 12, 1915. Serial No. 20,631.

To all whom it may concern:

Be it known that I, WILLIAM F. QUARTERS, a citizen of the United States, residing at Providence, in the county of Providence and 5 State of Rhode Island, have invented certain new and useful Improvements in Supports for Foot-Coverings, of which the following is a specification.

My invention relates to a device for supporting upon the foot, a shoe, slipper, or other foot covering.

The essential objects of my invention are facile detachment and entire removal of the device from the shoe when not in use there- 15 by making a special construction of shoe unnecessary; to prevent abrasion or the wearing of holes in the stocking of the wearer and the blistering of the wearer's heel due to the vibration of the back of the shoe; to ren- 20 der the device adjustable with respect to the size of the wearer's ankle, and to the relative forward location of any particular shoe heel, and adaptable to any size shoe; to maintain the material of the device in a flat position; 25 and to attain these ends in a device which does not contact with the upper arched surface of the foot whereby swelling is induced, which is easily applied and adjusted, inexpensive to construct, and which does not de- 30 face the material of the shoe.

To the above ends essentially my invention consists in such parts and combinations of parts as fall within the scope of the appended claim.

35 In the accompanying drawings which form a part of this specification, Figure 1 is a side elevation of a shoe engaged by my supporter, Fig. 2, a top plan view of the supporter, Fig. 3, a bottom plan view of the 40 sliding member and adjacent parts, Fig. 4, a section on line 4—4 of Fig. 3, Fig. 5, a side elevation of the adjustable portion of one loop, Fig. 6, a longitudinal section of the same, Fig. 7, a plan view of a modified form 45 of my support, and Fig. 8, a section on line 8—8 of Fig. 7.

Like reference characters indicate like parts throughout the views.

My invention is shown in connection with 50 a human ankle A, and a shoe or slipper B, provided with a heel b.

The support in present and preferred embodiment comprises a body formed from a continuous flat strip c of elastic webbing. 55 The strip, in the original form of an oblong loop, is given a half twist so that the strip

crosses itself flatly at an intermediate point d forming two loop portions E and F.

Embracing the inner portion of the loop F is a slide G composed preferably of a 60 triangular piece of elastic webbing whose end portions are overlapped against its back and retained by seams g forming two connected flat sleeves h inclined with relation to each other, whereby the portions of the strip 65 c adjacent the slide are maintained in overlapped and crossed position. As the strip is in slidable engagement with the sleeves, the slide in its movement along the loops changes the lengths of the loops relatively to 70 each other.

The ends of the strip c may be free to be manually tied, or may, as shown, be engaged to make the loop E a closed loop. The construction shown obviates the difficulty of 75 bending over to fasten free ends. These ends may be connected in a continuous strip or may have an adjustable connection. As shown, one end i of the strip is folded over one bar j of an open plate J and sewed upon 80 itself forming a retaining loop k. Over the opposite bar l of the frame slidably passes the strip c folded back to form a longer adjusting loop L. The second end of the strip terminates in a retaining loop m surrounding 85 a central cross bar n in an open frame N, which in this instance has fixed to its front an ornamental plate or ornament o. The strip c, in the formation of the loop L has a portion, as at p, passing behind the side bars 90 of the frame N and over the loop m on the bar n whereby friction prevents the accidental slipping of the material of the loop after the same has been adjusted.

To apply my holder the loop E is enlarged 95 by moving the slide G to the right, and the loop then passed up from below the shoe to a position surrounding the wearer's ankle A. The slide G is slid back toward its original position until its under face rests against the upper portion of the back of the shoe B. Then the loop F is downwardly stretched from the rear below the heel b and then released to assume its seat at the junction of the heel with the shoe instep, as 100 shown in Fig. 1.

The soft and elastic character of the member G prevents any injury to the surface of even a satin shoe. Its flat character combined with the flat disposition of the strip c prevents any bunching at the rear of the 105 ankle, and its movable character determines

the length of the loop F to fit any size shoe, or accommodate heels located at different distances from the rear of the shoe. Its rough rear face and elastic character prevents slipping on the shoe. The adjustable loop L accommodates the loop E to any particular size ankle.

Another form of my device which possesses some, but not all, the advantages of 10 the described form, is shown in Figs. 7 and 8. Herein the strip c is uncrossed between the loops, and the slide G has its sleeves h' parallel with each other.

It will be observed that by my device the 15 shoe is supported in a vertical direction at the heel and is forced rearwardly toward the heel by the lower portion of the support, whereby the entire shoe is maintained snugly

to the foot, and the usual tendency of the shoe to first leave the foot at the heel is thus 20 overcome.

What I claim is:—

A shoe support comprising two continuous loop portions, one of said loop portions arranged to embrace a shoe heel, the second 25 loop portion adapted to embrace an ankle, and a member slidably engaging the support intermediate the loop portions adapted to rest against the body of a shoe.

In testimony whereof I have affixed my 30 signature in presence of two witnesses.

WILLIAM F. QUARTERS.
